RECREATIONAL BUILDING OR THE LIKE

Mike Tecton, 5105 45th St. NW.,
Washington, D.C. 20016

Filed Oct. 24, 1965, Ser. No. 87,919

Term of patent 14 years

(Cl. D83—1)

FIG. 1 is a perspective view of a recreational building or the like, embodying my new design;

FIG. 2 is a right side elevational view thereof;

FIG. 3 is a top plan view thereof;

FIG. 4 is a front elevational view thereof;

FIG. 5 is a rear elevational view thereof.

I claim:

The ornamental design for a recreational building or the like, substantially as shown.
